(57) **CLAIM**

I claim the ornamental design for an outsole for a shoe, as shown and described.

DESCRIPTION

FIG. 1 is a bottom plan view of an outsole for a shoe showing my new design;

FIG. 2 is a left side view thereof;

FIG. 3 is a right side view thereof;

FIG. 4 is a front side view thereof;

FIG. 5 is a rear view thereof;

FIG. 6 is an enlarged perspective view of the area indicated as “6” in FIG. 1, the surface texture shown, being understood to extend across all of the stippled shapes throughout the bottom view; and,

FIG. 7 is an enlarged cross sectional view taken on line 7—7 of FIG. 6, the broken lines showing the interior surface illustrating the portion of the design that forms no part of the claim.

The broken line forming a curved trapezoidal shape in the arch area of FIG. 1–3, along with the parallel broken lines around the periphery in FIGS. 2–6 represent the internal boundaries of the design, with the lines themselves and the areas within them, forming no part of the claim.
